UNITED STATES PATENT OFFICE.

PHILIP K. WILLIAMS AND GEORGE S. HURST, OF GLASTONBURY, CONNECTICUT, ASSIGNEES TO THE J. B. WILLIAMS COMPANY, OF GLASTONBURY, CONNECTICUT, A CORPORATION OF CONNECTICUT.

POWDER-RECEPTACLE.

1,277,281.

Specification of Letters Patent.

Patented Aug. 27, 1918.

Application filed December 24, 1915. Serial No. 68,469.

To all whom it may concern:

Be it known that we, PHILIP K. WILLIAMS and GEORGE S. HURST, both citizens of the United States, and both residents of Glastonbury, in the county of Hartford and State of Connecticut, have invented a new and Improved Powder-Receptacle, of which the following is a specification.

Our invention relates to that class of dispensing receptacles more commonly used in connection with toilet powder, and an object of our invention, among others, is to provide a receptacle in which the packing or caking of the powder between the dome 10 and the cap is prevented and whereby free delivery of powder at all times in amounts as may be desired is insured.

One form of receptacle embodying our invention and in the construction and use of which the objects herein set out, as well as others, may be attained, is illustrated in the accompanying drawings, in which—

Figure 1 is a top plan view of our improved receptacle;

Fig. 2 is a like view with cap removed; Fig. 3 is a view in elevation of said receptacle; and

Fig. 4 is a view in elevation with the upper part cut away in central vertical section to illustrate the construction.

A form of receptacle in common use at the present time for holding and dispensing toilet powders comprises a can the top of which has a dome with openings for the outflow 35 of powder, this dome being inclosed within a cap, commonly screw threaded, which cap is also provided with an opening or openings for discharge of powder, which parts are arranged so that the openings in the dome 40 may be closed. In the use of such receptacles, more especially those employed for holding what are commonly known as talc powders, the powder becomes packed or caked between the dome and the under surface of the cap owing to the peculiar composition of the powder, and this results in closing the holes or openings and thus prevents a free discharge of the powder after 45 it has become so packed, and the difficulty 50 must therefore be removed.

Our improved can obviates this difficulty and effectually prevents the powder from becoming so packed as to prevent its free discharge at all times when desired, such

can being shown in the accompanying drawings in which the numeral 5 indicates a can body, 6 a top therefor having a dome 7 rising therefrom and preferably having a screw threaded wall to receive a screw threaded cap 8 that fits upon and incloses the dome. 55 Openings 9 are formed through the top of the dome, each opening being of such size that the powder will not have sufficient strength to pack and cover the opening but will fall through into the can. In the form 60 of construction herein shown three openings are provided separated each from the other by a very narrow bridge 10. These bridges support the crown 11 of the dome, which crown is slightly larger than a hole 12 in 65 the center of the cap 8 thereby leaving a very narrow margin 13 between the edges of the openings 9 and the edge of said hole. The parts thus formed provide a very little 70 surface upon which the powder may accumulate and the openings in the dome are of such size that when the cap is screwed to place practically all of the powder underlying the cap will be forced into the can and the rest will pass out through the opening 75 12 in the cap, and this effectually prevents 80 any clogging of the discharge openings from the receptacles.

As shown in Fig. 4 the crown 11 is rounded to project into the central opening or 85 hole in the cap, the edges of said hole being tapered to fit the rounded surface of said crown.

While we have shown and described herein a satisfactory construction of receptacle for accomplishing our purpose, this may be departed from to a greater or lesser degree and yet be within the spirit and intent of the invention.

We claim—

1. A receptacle including a top having a slot of circular form divided by narrow bridges, said slot forming a central portion which is shaped into a crown, said bridges being of a width merely to sustain the crown, a cap fitting said top and having a central opening of less diameter than said crown, and means for separating the meeting surfaces of the top and cap to permit flow of powder said slots being of a width to cause 100 all powder to fall into the box and clear the slots when the cap is closed.

2. A receptacle including a top having a

series of openings of a size to prevent caking of a powder across them, and with narrow bridges merely to support a crown, said bridges being of less area than said openings and narrow enough to prevent caking of powder upon them, a cap fitting said top, the latter having a crown at its center and said cap having a central hole of less diameter than the distance across said crown, and

means for separating the meeting surfaces 10 of the top and cap to permit flow of powder.

PHILIP K. WILLIAMS.
GEORGE S. HURST.
